DESIGN FOR A DESK STAND

Byrd R. Lewis, Paducah, Tex.

Application February 15, 1937, Serial No. 67,674

Term of patent 7 years

To all whom it may concern:

Be it known that I, Byrd R. Lewis, a citizen of the United States, residing at Paducah, in the county of Cottle and State of Texas, have invented a new, original, and ornamental Design for Desk Stands, of which the following is a specification, reference being had to the accompanying drawing, forming a part thereof.

In the drawing:

I claim:

The ornamental design for a desk stand as shown.

BYRD R. LEWIS.
